UNITED STATES PATENT OFFICE.

CLARENCE W. CUTLER, OF CHICAGO, ILLINOIS.

EYEGLASSES.

Application filed October 1, 1927. Serial No. 223,372.

This invention relates to improvements in eye-glasses, and more especially to means for attaching the same to the head of a wearer.

Although the invention is shown as applied to eye-glasses, it is to be understood that it is equally well applicable to spectacles, and the like. In the use of the term "eye-glasses", I am using the same broadly to cover any kind of frame for supporting lenses before the eyes of a wearer.

Among the features of my invention is the provision of simple, light, neat, effective and durable means for firmly and securely holding eye-glasses in place on the head of a wearer with a minimum of discomfort.

In those forms of devices embodying the features of my invention shown in the accompanying drawings

Figure 1 is a view in front elevation; Fig. 2 is a view on an enlarged scale, taken as indicated by the line 2 of Fig. 1; Fig. 3 is a view on an enlarged scale, taken as indicated by the line 3 of Fig. 1; Fig. 4 is a vertical sectional view of an optional rubber bulb for producing a vacuum; Fig. 5 is a view in front elevation of a modified form; Fig. 6 is a view on an enlarged scale, taken as indicated by the line 6 of Fig. 5; Fig. 7 is a view in front elevation of another modified form; Fig. 8 is a view in front elevation of still another modified form; Fig. 9 is a view on an enlarged scale, taken as viewed by line 9 of Fig. 8; and Figs. 10 and 11 are views in front elevation of additional modified forms.

Among the features of my invention is the provision of improved vacuum or suction cups, together with means for producing and maintaining suction therein. Another feature of my invention is the use of parts of the frame of the eye-glasses for affording air communication with the suction cups. Another feature of my invention is the provision of means for automatically producing continuous suction in the cups over a space of time, thus giving the wearer time to adjust the eye-glasses before losing the suction.

Another feature of my invention is the provision of spring means in connection with the frame, said spring means operating the suction producing means.

Other features and advantages of my invention will appear more fully as I proceed with my application.

In the device shown in Fig. 1, 10 indicates

a frame of the usual form supporting the lenses 11, 11. 12, 12, indicate rubber cups or flanges inset in the frame and adapted to bear against the sides of the nose of the wearer. Air communication is afforded from these cups through the passage 13 in the frame 10 to the suction producing means 14, shown in Figs. 1 and 3 as a cylinder with a piston 15 pressed outwardly by a spring 16. The piston 15 is provided with a spring valve controlled air by-pass 15^a of the usual form. A finger button 17 is provided for pushing the piston 15 inwardly to expel air from the cups 12. Upon release of the button 17, the spring 16 urges the piston outwardly to withdraw air from the cups 12 to produce a partial vacuum therein to cause the same to adhere to the sides of the nose.

The vacuum cylinder 14 is preferably provided with a restricted air outlet 18 or a restricted air inlet 19, as shown, to slow down the movement of the piston 15 even though the cups 12 be not in contact with the nose. By this construction, it will be seen that even though the button 17 is released, the cylinder 14 will continue to withdraw air slowly from the cups 12, thus giving the wearer an appreciable time to adjust the glasses in position and set the cups 12 securely in place, so that the vacuum when produced will not be quickly lost.

In Fig. 4 is shown an ordinary rubber bulb 14^a which may be used for producing a vacuum instead of the cylinder 14. This bulb also may be provided with a restricted air inlet 19^a, as shown, to slow the action.

In Figs. 5 and 6, I have shown another form of device in which the eye-glass frame is provided with an additional curved bridge member 20 extending from lens to lens. This member is provided with two rubber cups 12^a, 12^b, adapted to be placed against the forehead of the wearer. The member 20 is provided with an air passage 13^a leading to a suction cylinder 14, as shown in Figs. 1 and 3. In the device shown in Fig. 5, the vacuum cylinder 14 is connected to the frame 20 by means of a flexible tube 21.

The device shown in Fig. 7 is substantially the same as that shown in Fig. 5, except that the bridge member 20^a is somewhat resilient or springy so that in addition to the vacuum cups 12^b, the bridge member 20^a may be slightly straightened to separate the nose clamps 21^a. When released, the nose clamps 21 will assist in holding the eye-

glasses in place by gripping the sides of the nose in the usual manner.

In the device shown in Fig. 8, there is provided a bridge member 20^b, the lens frames 22 being hinged to the ends thereof, at 23. 12°, 12°, indicate the vacuum cups (see Fig. 9), each of such cups being in communication with a small vacuum cylinder 24, provided with a piston 25 and a spring 26, in the usual manner. The piston 25 is adapted to be operated by a piston rod 27 which has a pivotal connection at 28, with the lens frames 22. It will be seen that pivoting the lens frames 22 on the pivots 23 to separate the nose clamps 21^b will compress the vacuum cylinders, and that upon releasing, the cylinders will operate to produce a partial vacuum in the cups 12° against the forehead, and at the same time 20 the nose clamps 21^b will grip the sides of the nose.

In the form of device shown in Fig. 10, I provide two vacuum cups 30 communicating with a double vacuum cylinder 31, 25 having two pistons operated by the finger clamps 32. Air communication is afforded between the cups 30 and the cylinder 31 through the passage 33 in the frame.

In the form shown in Fig. 11, the bridge 30 member 34 is slightly resilient, and instead of providing the finger clamps 32, as shown in Fig. 10, I let the piston rods 35 bear against shoulders 36 on the lens frames. As the frames 37 are bent slightly upwardly 35 to the positions indicated by 37^a, the pistons in the vacuum cylinder 38 are compressed so that when the frames are released the pistons will separate to produce a vacuum in the cups 39. A release of the lens frames 40 will also cause the bridge member 34 to bend back into its normal shape, thus causing the cups 39 to press more securely against the sides of the nose.

While I have shown and described certain 45 embodiments of my invention, it is to be understood that it is capable of many modifications. Changes, therefore, in the construction and arrangement may be made without departing from the spirit and scope 50 of the invention as disclosed in the appended claims, in which it is my intention to claim all novelty inherent in my invention.

What I claim as new and desire to secure by Letters Patent, is:

55 1. In eye-glasses; a frame; lenses carried by said frame; a vacuum cup carried by said frame and adapted to be pressed against the face of a wearer; and means for producing a partial vacuum in said vacuum cup, air communication between the vacuum cup and vacuum producing means extending through a portion of said frame.

60 2. In eye-glasses; a frame; lenses carried by said frame; a vacuum cup carried by said frame and adapted to be pressed against the

face of a wearer; means for automatically slowly withdrawing air from said vacuum cup, communication between said cup and said air withdrawing means extending through a portion of said frame. 70

3. In eye-glasses; a frame; lenses supported by said frame; and means for attaching said frame and lenses to the face of a wearer, said means comprising a vacuum cup adapted to be placed against the face, 75 and means for automatically slowly withdrawing air from said cup.

4. In eye-glasses; a frame; lenses supported by said frame; a pair of vacuum cups carried by said frame and adapted to 80 contact with the sides of the nose of a wearer; and means for slowly withdrawing air from said vacuum cups, air communication between said cups and air withdrawing means extending through a portion of said frame. 85

5. In eye-glasses; a frame; lenses carried by said frame; a vacuum cup carried by said frame and adapted to be placed against the face of a wearer; and means for automatically slowly withdrawing air from 90 said vacuum cup, said means comprising a cylinder with a spring-pressed piston therein, and means for checking the movement of said piston when pressed by said spring. 95

6. In eye-glasses; a frame; lenses carried by said frame; a vacuum cup carried by said frame and adapted to be placed against the face of a wearer; and means for automatically slowly withdrawing air from said 100 vacuum cup, said means comprising a cylinder with a spring-pressed piston therein, and means for checking the movement of said piston when pressed by said spring, 105 said checking means comprising a restricted air passage between said cylinder and the atmosphere.

7. In eye-glasses; a frame; lenses carried by said frame; a pair of vacuum cups carried by said frame; said cups adapted to be 110 placed against the face of a wearer; and spring means for withdrawing air from said cups, said means adapted to be compressed by bending of the frame to separate the lenses. 115

8. In eye-glasses; a frame; lenses carried by said frame; a pair of vacuum cups carried by said frame; said cups adapted to be placed against the face of a wearer; and spring means for withdrawing air from 120 said cups, said means adapted to be compressed by bending of the frame to separate the lenses. said frames also carrying nose clamps adapted to be pressed together to grip the nose upon expansion of said spring- 125 pressed air suction means.

In witness whereof, I have hereunto set my hand and seal, this 29th day of September, 1927.

CLARENCE W. CUTLER.
